(57) **CLAIM**

The ornamental design for a fuse holder, as shown and described.

DESCRIPTION

FIG. 1 is a perspective view of a fuse holder;
FIG. 2 is a front elevation view of the fuse holder of FIG. 1;
FIG. 3 is a rear elevation view of the fuse holder of FIG. 1;
FIG. 4 is a right elevation view of the fuse holder of FIG. 1;
FIG. 5 is a left elevation view of the fuse holder of FIG. 1;
FIG. 6 is a top plan view of the fuse holder of FIG. 1; and,
FIG. 7 is a bottom plan view of the fuse holder of FIG. 1.
The broken lines in the drawings are for the purpose of illustrating portions of the article that form no part of the claimed design.

1 Claim, 7 Drawing Sheets
